UNITED STATES PATENT OFFICE.

NICHOLAS MULLER, OF NEW YORK, N. Y.

IMPROVEMENT IN TOY BLOCKS FOR OBJECT-TEACHING.

Specification forming part of Letters Patent No. 143,835, dated October 21, 1873; application filed July 5, 1873.

To all whom it may concern:

Be it known that I, NICHOLAS MULLER, of the city, county, and State of New York, have invented a new and useful Improvement in Blocks for Object-Teaching and Amusement, of which the following is a specification:

This invention relates to apparatus designed to facilitate the study of geometry, in the formation of geometrical figures, and to familiarize the minds of both the young and old with such figures, and also to afford recreation and amusement; and it consists in two triangular-shaped blocks, made of any material and of any size, by the use of which (and no other) various figures are formed by laying them together, as hereinafter described.

In the drawing, Figures 1 and 2 represent the pieces or blocks, both triangles, but of different shape and superficial area.

Fig. 1 has two equal sides, *a a*, which form an acute angle, *b*. These sides are equal to the two sides *c c* of Fig. 2, which two sides are also equal. The hypotenuse of these triangles is marked *d*. The relation of these blocks to each other is such that when they are placed together, as seen in the figures from 3 to 7, and in various other combinations not shown in the drawings, regular geometrical polygons and figures are produced from a

simple triangle of the exact form and proportions of Fig. 1, as seen in Figs. 4 and 6, to a perfect pentagon, and other and more complicated geometrical and ornamental forms of almost endless variety. Instruction and amusement may thus be combined, and the intellectual faculties exercised in producing the various forms.

The sides of the blocks, Figs. 1 and 2, may be of different colors, and may be placed so that the figures will present a more ornamental appearance than they would if but one color appeared.

Having thus described my invention, I claim as new and desire to secure by Letters Patent—

The combination of two sets of toy blocks, one being formed of acute-angled and the other of obtuse-angled blocks, all the sides which embrace the obtuse and smallest acute angle being equal, as set forth, whereby pentagons, pentagrams, and an almost infinite variety of proportional geometrical forms can be constructed.

NICH. MULLER.
